PHOTOGRAPHIC FLASHLAMP UNIT

Lester F. Anderson and Sedgwick R. Bennett, Williamsport, and Donald W. Hartman, Warrensville, Pa., assignors to Sylvania Electric Products Inc., a corporation of Delaware

Filed May 19, 1965, Ser. No. 85,357

Term of patent 14 years

(Cl. D61—1)

FIG.1

The dominant features of our design reside in the portion shown in full lines.

We claim:

The ornamental design for a photographic flashlamp unit, as shown and described.
